UNITED STATES PATENT OFFICE.

HARRY S. WALKER, OF CORVALLIS, OREGON, ASSIGNOR, BY DIRECT AND MESNE ASSIGNMENTS, OF THREE-EIGHTHS TO JAMES R. CHAMBERS, OF CORVALLIS, OREGON, AND ONE-FOURTH TO LOTTIE A. REED, OF MEDFORD, OREGON.

MOVING-PICTURE SCREEN.

1,094,613.

Specification of Letters Patent. Patented Apr. 28, 1914.

Application filed November 27, 1912. Serial No. 733,821.

To all whom it may concern:

Be it known that I, HARRY S. WALKER, a citizen of the United States, residing at Corvallis, in the county of Benton and State 5 of Oregon, have invented a new and useful Moving-Picture Screen, of which the following is a specification.

The invention relates to improvements in screens for displaying moving pictures.

- 10 The object of the present invention is to improve the construction of screens for displaying moving pictures, and to provide a simple, inexpensive and efficient apparatus, designed for use on the stage for converting 15 the same into a moving picture cabinet, and capable of enabling the stage to be easily and quickly cleared for permitting the same to be used for vaudeville and other staged amusements.
- 20 A further object of the invention is to provide a moving picture screen of this character, equipped with means for enabling pictures of a better character and more life like to be shown in a lighted room with all the 25 advantages thereof and without the injurious effect on the eyes and optic nerves resulting from the flashing of the lights in a darkened room or auditorium.

With these and other objects in view, the 30 invention consists in the construction and novel combination of parts hereinafter fully described, illustrated in the accompanying drawing, and pointed out in the claims here- 35 to appended; it being understood that various changes in the form, proportion, size and minor details of construction, within the scope of the claims, may be resorted to without departing from the spirit or sacrificing any of the advantages of the invention.

40 In the drawing:—Figure 1 is a perspective view of a stage equipped with a moving picture screen, constructed in accordance with this invention. Fig. 2 is a central vertical sectional view of the same. Fig. 3 is 45 a vertical sectional view of a portion of the apparatus showing the inner flexible walls or lining partially elevated.

Like numerals of reference designate corresponding parts in all the figures of the 50 drawing.

In the accompanying drawing in which is illustrated the preferred embodiment of the invention, 1 designates a flexible screen mounted upon a spring actuated roller 2, ex-

tending across the top portion of a stage 3 55 at the back thereof adjacent to the rear wall 4 of the same and supported in suitable brackets 5 of the ordinary construction. The screen, which is adapted to be raised and lowered in the same manner as an ordinary 60 window shade, is designed to be provided with a metallic picture receiving surface consisting of powdered aluminum applied over an opaque coating, which is first put on the screen. Gold bronze may also be em- 65 ployed and it has been found most advan- tageous in displaying old pictures. The flexible screen may, however, be equipped with any other suitable surface.

The screen is framed by a flexible rectangular inner lining constructed of black cloth or other suitable material and constituting a light absorbing cabinet and consisting of a horizontal bottom portion 6, vertical side walls or portions 7 and a horizontal top 75 wall or portion 8, which is preferably suitably secured at the top of the stage. The black inner lining is adapted to absorb reflected lights and throw a shadow on the screen, which with shaded lights will enable 80 moving pictures to be exhibited in a lighted room. This will prevent the misconduct which frequently occurs in darkened rooms, and will enable pictures to be enjoyed with less tiresome effect on the eyes and at the 85 same time afford a person a view of the surroundings and enable them to avoid sitting in close proximity to undesirable persons. Also the exhibiting of pictures in substan- 90 tially the same light that is used in display- 95 ing the pictures will render them more life like. In practice any suitable lights may, of course, be employed, and they are equipped with shades arranged to light up the room or auditorium and at the same time leave the screen in the shadow.

The flexible inner lining is maintained in proper position in front of the screen by lower horizontal corner rods 9, provided at their inner ends with projecting points or 100 spurs 10 adapted to be embedded in the rear wall of the stage, whereby the rods 9 are detachably secured in position. Any other suitable means, however, may be employed for fastening the rods at the corners of the 105 flexible screen framing lining. When the horizontal rods are detached the flexible lining is adapted to be raised out of the way to

enable the stage to be used for vaudeville or other purposes. The flexible lining is raised by ropes or cords 11, located at the outer faces of the side walls of the screen and passing over guide pulleys 12 and connected with the flexible lining at the lower ends of the vertical sides. The pulleys 12 are suitably mounted at the top of the stage and any suitable means may be provided for securing the cords or ropes to hold the flexible lining in its elevated position. When the cords or ropes are pulled to elevate the lining, the bottom and sides thereof are raised and are held at the upper portion of the stage out of the way. By this construction the screen and the lining may be mounted at any desired portion of a stage, and they will not interfere with the use of the same for other purposes.

20 In order to give the picture a perspective and increase the life like character of the same, the inner flexible lining is equipped at the inner edge of its side walls 7 and top portion 8 with colored electric lights 13, mounted on and carried by the flexible lining and equipped with shades 14, constructed of sheet metal or other suitable material and arranged to prevent the light from being thrown upon the screen. The shade consists of a shell provided with an attaching collar 15, which clamps the electric lights at the base thereof. The shades for the lights, which illuminate the room or auditorium, may be of a similar construction but made on a larger scale. The colored electric lights at the inner edges of the side walls of the flexible lining are carried upwardly with the same when the lining is folded, and the glass bulbs may be made of sufficient strength to prevent them from being easily broken, or they may be equipped with guards of any ordinary construction.

This application is a continuation as to certain broad features of the invention of my prior application, filed Jan. 21, 1910, Serial No. 539,353.

What is claimed is:—

1. In an apparatus of the class described, the combination with a stage, of an approximately rectangular screen having a picture

receiving surface and provided at the top with a roller and adapted to be rolled thereon to arrange it out of the way of the stage, a collapsible light absorbing lining composed of a relatively fixed top portion, flexible side portions and a bottom portion connecting the sides, means for detachably securing the side and bottom portions in position, and means connected with the side and bottom portions for raising them simultaneously and together to the top of the stage when the screen is rolled up.

2. An apparatus of the class described including a rectangular screen, a rectangular lining of light absorbing material located in advance of and extending around the screen and composed of a fixed top portion, and a movable bottom and side walls, horizontal rods detachably secured in the lower corners of the lining and holding the same in position, and means connected with the lining for raising and lowering the same.

3. An apparatus of the class described including a rectangular screen, a rectangular lining of light absorbing material located in advance of and extending around the screen and composed of a fixed top portion, and a movable bottom and side walls, means detachably connected with the lining at the bottom thereof for holding the same in position, and hoisting means connected with the lining at the lower ends of the side walls thereof for raising and lowering the lining and for supporting the same in an elevated position out of the way.

4. An apparatus of the class described including a screen having a picture receiving surface, a light absorbing lining located in advance of the screen and extending around the same, colored lights arranged in intervals at the inner portion of the lining, and shades interposed between the lights and the screen.

In testimony, that I claim the foregoing as my own, I have hereto affixed my signature in the presence of two witnesses.

HARRY S. WALKER.
